UNITED STATES PATENT OFFICE

1,923,326

FIRE EXTINGUISHER

Harry Lee Parrish, Nashville, Tenn.

Application September 3, 1932. Serial No. 631,696

6 Claims. (Cl. 169—26)

This invention relates to an automatic fire extinguisher.

The primary object of the invention is to provide a fire extinguisher which is automatically operated by a thermo element upon the latter becoming heated, thereby providing for the operation of the fire extinguisher at any desired temperature.

A further object of the invention is to provide 10 a fire extinguisher embodying a releasable supporting means for a grenade containing a fire extinguishing chemical, such means operating when released to dash the grenade against a rigid obstruction to burst the grenade and release 15 the contents thereof, and further operating to release a normally latched escapement mechanism for sounding an alarm.

Further objects of the invention are to provide 20 a fire extinguisher of the character aforesaid which is comparatively inexpensive to manufacture, and which is so constructed and arranged that the parts thereof will be substantially free from deterioration during long periods of inactivity.

25 A fire extinguisher in accordance with this invention is illustrated in the accompanying drawings, in which:

Figure 1 is a front elevation of the fire extinguisher.

30 Figure 2 is a central, vertical section therethrough.

Figure 3 is a perspective thereof.

Figure 4 is an enlarged fragmentary perspective of the grenade supporting means.

35 In the embodiment of the invention shown in the drawings, the numeral 1 indicates a base plate preferably elongated in shape and adapted to be secured in an upright position to a wall or the like. Projecting from the forward face of the base plate, substantially midway between its ends, are a pair of opposed ears 2 which preferably constitute the end portions of a U-shaped bracket.

40 Pivotally supported by the ears 2 are a pair of supporting arms 3 for a grenade 4 adapted to contain a fire extinguishing chemical such as carbon tetrachloride. Preferably the arms 3 are pivoted to the ears 2 by means of a right angularly extending portion 5 at the inner end of one of the arms 3, such portion 5 extending through and being journaled in the ears 2. The other arm is pivotally connected at its inner end to the free end of the portion 5 in a manner to permit swinging movement thereof toward and from 45 the arm having the right angularly extending

portion 5. The outer ends of the arms 3 are formed into loops or rings 6 which are adapted to embrace the grenade 4 on opposite sides thereof to hold the grenade between the loops, the latter being yieldingly urged toward each other 60 by means of a tension element such as a coil spring 7 extending between and having its ends secured to the respective arms 3. The spring 7 extends through a rigid, tubular housing 8.

The arms 3 normally are maintained in a substantially upright position as shown in full lines in Figures 2 and 3 by means of a lug 9 on the extension 5, such lug bearing against an end face of a trigger member 10. The trigger member 10 is pivotally connected with the base plate 1, 70 preferably by means of a pair of ears 11 which are similar to the ears 2, and which project from the forward face of the base plate above the ears 2. The lower end of the trigger member 10 is urged away from the base plate by means of a spring 12, whereby the lower end face of the member 10 normally is disposed within the path of the lug 9 to maintain the arms 3 in their upright position. The upper end of the trigger member 10 is disposed adjacent a thermo element 75 13 carried by the base plate 1, such thermo element acting when expanded by heat to force the lower end of the trigger member 10 inwardly against the action of the spring 12 to release the lug 9, thereby permitting the arms 3 to fall by 80 gravity about their pivotal connection with the ears 2.

When the arms 3 fall to the position shown in dotted lines in Figures 2 and 3, the grenade 4 is carried therewith and forcibly dashed against a rigid obstruction 14, whereby the grenade is broken and the contents thereof spilled for the purpose of extinguishing the fire which caused the operation of the thermo element 13. Preferably the obstruction 14 forms a part of a rigid 90 strap 15 which is secured to the base plate 1, and which has an arcuate upper end portion 16 projecting forwardly and upwardly from the base plate 1 in spaced relation to the housing 8. Secured to the inner face of the arcuate portion 16 100 is a similarly shaped shield 17 of resilient metal which extends to a point in proximity to the trigger member 10, and is disposed adjacent the path of travel of the housing 8 during the movement of the arms 3.

Carried by the base plate 1 is a housing 18 for an escapement mechanism indicated fragmentarily at 19, and which may be of any well known construction. The escapement mechanism normally is latched against movement and is adapt- 110

ed to operate a hammer 20 when released to ring a bell 21. The means employed for latching the escapement mechanism is a lug 22 projecting from a leaf spring 23 and normally maintained 5 thereby within the path of movement of a vibrating arm 24 secured to the same pivot member 25 that supports the hammer 20. The leaf spring 23 is secured within the housing 18 and projects therefrom into the path of movement of one of 10 the arms 3 whereby the spring is depressed when the arm 3 falls about its pivot, thereby moving the lug 22 out of its latching position with respect to the arm 24 and permitting the escapement to operate in the usual manner which causes 15 the sounding of an alarm by the bell 21. The escapement mechanism per se forms no part of the present invention and may be either of the well known mechanical or electrical types.

While the embodiment of the invention herein 20 illustrated and described is to be considered as a preferred example of the same, it is to be understood that such departures from the arrangement shown may be made as fall within the scope of the appended claims.

25 I claim:

1. A fire extinguisher comprising, a pair of grenade supporting members pivotally mounted as a unit and having a normal tendency to move in one direction, one of said members further being pivoted for movement toward and from the other member, tension means urging the said one member toward the other member for gripping a grenade between the members, a trigger releasably latching said members against movement, a thermo element for operating said trigger to release said members, and a rigid obstruction within the path of movement of said members.

2. A fire extinguisher comprising, a pivoted 40 grenade supporting member having a normal tendency to move in one direction about its pivot, a trigger releasably latching said member against such movement, a thermo element for operating said trigger to release said supporting member, a rigid obstruction within the path of movement of said supporting member, an escapement mechanism operated bell, and means normally latching said escapement mechanism against operation, said means being released by the movement 50 of said member about its pivot.

3. A fire extinguisher comprising, a pivotally 55 mounted member adapted to support a grenade and having a normal tendency to move in one direction, a trigger releasably latching said mem-

ber against such movement, a rigid obstruction within the path of movement of the grenade supported by said member, an escapement mechanism operated bell, means normally latching said escapement mechanism against operation and having a part thereof projecting into the path of movement of said grenade supporting member, and a thermo element for operating said trigger to release said member, said member operating during its movement to dash the grenade supported thereby against said obstruction and to move said part projecting into its path for releasing the latching means for said escapement mechanism.

4. A fire extinguisher comprising, a pair of 80 grenade supporting members pivotally mounted as a unit and having a normal tendency to move in one direction, one of said members further being pivoted for movement toward and from the other member, a coil spring urging the said one member toward the other member for gripping a grenade between the members, a housing encircling said spring, an arcuate shield adjacent said housing, a trigger normally latching said members against movement, a thermo element 90 for operating said trigger to release said supporting members, and a rigid obstruction within the path of movement of said supporting members.

5. A fire extinguisher comprising, a pair of 95 grenade supporting members having a normal tendency to move in one direction, one of said members being pivoted for movement toward and from the other member, tension means urging the said one member toward the other member for gripping a grenade between the members, 105 means normally holding the members against movement in the said one direction and operating when subjected to excessive heat to release the members, and an obstruction within the path of movement of said members.

6. A fire extinguisher comprising, a grenade 110 supporting member having a normal tendency to move in one direction, means normally holding said member against such movement and operating when subjected to excessive heat to release the member, an obstruction within the path of movement of said member, a normally inactive 115 alarm device, and means having a part thereof projecting into the path of movement of said member for rendering the alarm device active 120 upon movement of said member into contact with said projecting part.
